UNITED STATES PATENT OFFICE.

JOHN S. DE LONG, OF OSBORN, OHIO.

WEEDER AND SOIL-PULVERIZER.

1,081,437.

Specification of Letters Patent. Patented Dec. 16, 1913.

Application filed July 2, 1913. Serial No. 777,083.

To all whom it may concern:

Be it known that I, JOHN S. DE LONG, a citizen of the United States, residing at Osborn, in the county of Greene and State of Ohio, have invented certain new and useful Improvements in Weeders and Soil-Pulverizers, of which the following is a specification, reference being had to the accompanying drawings.

10 This invention relates to new and useful improvements in weeders and more particularly to a combined weeder and soil pulverizer and the object of the invention is to provide a device of the above character 15 which is especially adapted for use in pulverizing the soil and destroying small weeds between the rows and around the plants.

Another object of the invention is to provide a weeder of the above character which 20 will possess advantages in points of efficiency and durability, is inexpensive to manufacture and, at the same time, is simple and efficient in operation.

With the above and other objects in view, 25 the invention consists in the novel features of construction, combination and arrangement of parts as will be hereinafter referred to and more particularly pointed out in the specification and claims.

30 In the accompanying drawings forming a part of this application, Figure 1 is a top plan view of a cultivator constructed in accordance with my invention. Fig. 2 is a front elevation. Fig. 3 is a longitudinal 35 sectional view. Fig. 4 is a detail perspective view of one of the weeding knives. Fig. 5 is a longitudinal sectional view through one of the shafts. Fig. 6 is a detail perspective view of one of the spider-pronged 40 wheels. Fig. 7 is a detail perspective view illustrating a modified form of spider disk wheel. Fig. 8 is a detail perspective view illustrating still another modified form of spider disk wheel.

45 Referring more particularly to the drawings, 1 indicates a handle member, to the outer end of which is secured a transverse handle bar 2 and to the inner end thereof are secured the spaced parallel arms 3, the 50 outer ends of which are downwardly curved, as shown at 4. Angular supporting brackets 5 are provided, the inner ends of which are secured to the arms 3, adjacent the handle, by means of bolts 6, the outer ends of said 55 brackets being downwardly curved as shown

at 7, to conform to the curvature of the outer ends of the arms 3.

A pair of longitudinal axles 8 are provided and arranged between the outer ends of the brackets 5 and the arms 3, the ends 66 of said axles being rotatably mounted within suitable bearings formed in the lower ends of the brackets 5 and the arms 3 and securely held against longitudinal movement by means of the pins 9. Rotatably mounted 65 upon the shafts and arranged between the outer ends of the brackets 5 and the arms 3, are a plurality of disks 10, said disks being provided upon one side thereof with the radially arranged sockets 11 in which 70 are mounted the inner ends of the radially projecting teeth 12, said teeth being securely retained within the sockets 11 by means of the set screws 13, any other well known form of fastening means being used, if desired. From this it will be seen that pressure exerted against the handle bar 2 will push the frame of the weeder forwardly and rotate the disk 10, the teeth 12 engaging within the surface of the soil and as they 75 move upwardly, they will pry the soil loose and any small weeds or undesirable plants will be readily removed from the soil to the top of the ground, where they will provide sufficient mulching for the soil. 85

Removably clamped to the side portions of the brackets 5 and arranged at the rear of the disks 10 are the weeding knives 14, the shank portions of said knives being securely held in position by means of the 90 clamps 15 which are carried on the side portions of the brackets 5 and in which the shank portions of the knives are removably arranged. When the knives 14 are disposed in inoperative position, they are arranged 95 above the frame and the lower ends thereof are disposed upon a level with the shafts 8 and rotatably mounted within the lower ends of the shank portions of the knives 14, is a second shaft 16, which is arranged at the rear and in spaced relation to the shafts 8 and upon which are mounted the disks 17. The disks 17 are similar in construction to the disks 10 and are provided with a plurality of radially projecting teeth 100 12' which are adapted to engage with the soil upon the forward movement of the weeder to thoroughly loosen the same. 105

From the above, it will be readily apparent that the disks 17 are preferably used in 110

place of the knives 14, under certain conditions of the soil but, on the other hand, when it is desired to use the weeding knives 14, the shank portions thereof are withdrawn 5 from the clamps 15 and inserted from the under side of the frame, so that the knives may be readily arranged in their operative position at the rear of the disks 10. The two disks which are arranged adjacent the 10 inner ends of the shaft 8, are provided upon their peripheries with the rims 18. Mounted upon the inner ends of the shafts 8 and projecting at right angles thereto, are the arms 19, the inner ends of which are bifurcated, 15 as shown at 20 to form the spaced ears 21, adapted to be arranged upon opposite sides of the lower ends of the arms 3 and mounted upon the shafts 8, the arms 19 being securely held in their operative position by means of 20 the cotter pins 22 arranged in the ends of the shafts.

Mounted upon the outer ends of the arms for rotation, are the hubs 23 which are provided with a plurality of radially projecting teeth 24 adapted to engage the teeth 12 upon the two disks arranged at the inner ends of the shafts 8, so that upon the rotation of the disks 10, the hubs 23 will be rotated through the engagement of the teeth, 30 the teeth 24 loosening the soil within the rows and between the plants, while the teeth 12 upon the disks 10 will loosen and pulverize the soil upon opposite sides of the rows. The hubs 23 and the arms 19 may be 35 quickly and readily removed from the inner ends of the shafts 8 and the spider-pronged wheels 25 may be mounted upon the inner ends of the shaft and used in place of the hubs 23 and the teeth 24. From the illustration shown in the accompanying drawings, 40 it will be readily apparent that the outer ends of the teeth upon the wheels 25 are inwardly curved, as shown at 26, so that upon the rotation of the wheels, the soil 45 around the plants may be readily loosened and by having the outer ends of the teeth inwardly curved, it will loosen the soil more closely about the plants than it would do if the teeth were straight.

50 In Fig. 7, I have illustrated a slightly modified form of the spider-pronged wheel in which the wheel consists of two clamping plates 27', the opposed faces of which are provided with suitable curved grooves adapted to receive the intermediate portions of the teeth 28. The teeth 28 are formed in pairs and constructed of a single length of heavy wire or a rod, the intermediate portion of which is bent upon itself to form a 55 curved portion, as shown at 29, which is adapted to be disposed within the grooves formed in the inner faces of the plates 27'. These plates 27' are securely clamped together by means of a bolt 30 and it will be 60 understood that one or more of these bolts 65

may be used and if desired, they may be so arranged that the bolt will pass through the plates at a point inside of the curved portion 29, thus leaving a central opening in the plates 27 whereby they may be readily mounted upon the axles 8 or 16. It will also be apparent that these spider pronged wheels may be used in place of the disks 10 and 17 if desired. It will be apparent from the above that these disks may be quickly and readily mounted upon the axle or removed therefrom. 70 75

In Fig. 8, I have illustrated another modified form of the spider disk wheel which includes a hub member 31 having the radially projecting spokes 32 secured thereto, said spokes being securely retained in spaced relation at their outer ends by means of the annular band 33. The band 33 is provided in its central portion with a plurality of circularly arranged openings 34 through which the spokes 32 are adapted to project. This band 33 is preferably arranged midway between the outer ends of the spokes and the hub 31. It will be apparent that the band 33 80 85 not only retains the spokes in their relative positions, but serves to strengthen the wheel as a whole. 90

From the above description taken in connection with the accompanying drawings, 95 it will be readily apparent that I have provided a simple and durable weeder and soil pulverizer wherein the soil between the rows and around the young plants may be quickly and readily pulverized and eliminated of 100 weeds. It will also be apparent that should the disk 10 be arranged upon the axles 8 at an angle with respect to the frame of the weeder, the teeth 12 will have a tendency to engage more deeply into the soil and stir 105 the same more thoroughly and destroy even the larger weeds between the rows of the young plants. It will also be apparent that the spider-pronged wheels 25 may be quickly and readily substituted when desired for the 110 hubs 23 and the teeth 24. My improved weeder, as above described and shown in the accompanying drawings, is extremely simple and durable in construction and can be manufactured at a comparatively low cost. 115

While I have shown and described the preferred form of my invention, it will be obvious that various changes in the details of construction and in the proportions may be resorted to for successfully carrying my 120 invention into practice without sacrificing any of the novel features or departing from the scope of the appended claims.

Having thus described this invention, what is claimed is:—

1. A weeder including a handle member, spaced parallel arms secured thereto, angular supporting brackets secured to said arms, the outer ends of said brackets and arms being downwardly curved and arranged in 130

longitudinal alinement, shafts rotatably mounted in the outer ends of the arms and brackets and arranged upon opposite sides of the center of the handle, and cultivator disks mounted upon said shafts and adapted to rotate therewith.

2. A weeder including a handle member, spaced parallel arms secured thereto, angular supporting brackets secured to said arms, 10 cultivator disks rotatably mounted between the outer ends of the arms and brackets, a rotatable shaft supported by said brackets and arranged at the rear of the cultivator disks, and a second set of cultivator disks 15 mounted upon said shaft and adapted for rotation therewith.

3. A weeder including a handle member, spaced parallel arms secured thereto, supporting brackets secured to the arms, the outer ends of said arms and brackets being curved and arranged in longitudinal alinement, shafts rotatably mounted between the outer ends of the arms and brackets and disposed on opposite sides of the center 20 thereof, cultivator disks mounted upon said shafts and adapted for rotation therewith, weeding knives, the shank portions of said 25

knives being adjustably mounted upon the side portions of the brackets, a shaft journaled in the lower ends of said shank portions and arranged at the rear of the cultivator disks, and a second set of cultivator disks mounted upon said shaft and adapted for rotation therewith.

4. A weeder including a handle member, 35 spaced parallel arms secured thereto, angular supporting brackets secured to said arms, shafts rotatably mounted within the outer ends of said arms and brackets, cultivator disks mounted upon said shafts and adapted 40 for rotation therewith, outwardly projecting arms removably mounted upon the inner ends of said shafts, hubs rotatably mounted upon the outer ends of said arms, and radially projecting teeth carried by said hubs 45 and adapted to be engaged by certain of said cultivator disks to rotate the same.

In testimony whereof I hereunto affix my signature in the presence of two witnesses.

JOHN S. DE LONG.
